(57) **CLAIM**

The ornamental design for a speaker housing, as shown and described.

DESCRIPTION

FIG. 1 is a perspective view of a speaker housing showing my new design;

FIG. 2 is a front elevational view thereof;

FIG. 3 is a side elevational view thereof, the opposite side elevational view being a mirror image thereof; and,

FIG. 4 is a top plan view thereof.

The broken line showing of the circles, the collar and the cord are for illustrative purposes only and form no part of the claimed design.

1 Claim, 2 Drawing Sheets

FIG. 2

FIG. 1

FIG. 4**FIG. 3**
